UNITED STATES PATENT OFFICE

HARRY J. COCKS, OF DES MOINES, IOWA, ASSIGNOR OF ONE-HALF TO NATHANIEL C. BARNES, OF DES MOINES, IOWA

DISPENSING APPARATUS

Application filed October 29, 1927. Serial No. 229,593.

The object of my invention is to provide a dispensing apparatus wherein liquid soap or creams may be dispensed with regular shots or charges, the parts being simple, 5 durable and comparatively inexpensive in construction.

More particularly it is my object to provide an inner container within an outside container wherein air pressure may be used 10 for forcing the bottom of the inside container upwardly wherein the contents from within the inside container, may be discharged and dispensed by manually operating a valve controlled outlet.

Still a further object is to provide a pump mechanism forming a part of the dispensing apparatus wherein the inside container may be subjected to air pressure for causing its bottom to move and thus discharge the 20 contents from within the inside container when desired.

Still another object is to provide an inside container having a movable bottom therein arranged with a downturned flange 25 so that a chamber is formed below the bottom of the inside container and the base of the dispensing apparatus for receiving a sufficient amount of air under pressure to move the bottom upwardly when the valve controlled outlet is in open position.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:—

Figure 1 is a top plan view of my improved dispensing apparatus.

Figure 2 is a central vertical sectional view taken on the line 2—2 of Figure 1.

Figure 3 is an enlarged detail view of the check valve forming a part of the pump construction and mounted in the base of the dispensing apparatus.

Figure 4 is a perspective view of the bottom element which is mounted within the inside container and

Figure 5 is a perspective view, parts being

broken away and shown in section, disclosing the assembly of the bottom and the inside container.

In the accompanying drawings, I have used the reference character A to indicate 55 generally a base having a cylinder opening 10 formed therein. The cylinder opening 10 is partially closed at one end with a cap or plug 12 and has a narrow web 14 formed in its other end. The web 14 is provided 60 with an opening 16 adapted to communicate with an opening 18 formed in a check valve plug 20.

The plug 20 is adapted to be screw threaded 65 into the base A and is provided with a ball valve 22. The base A has a passageway 24 in communication with the passageway 18 of the plug 20 and serves as a means of communication between the pump construction and the interior of the dispensing apparatus as will hereafter be more fully set forth.

Slidably mounted within the plug 12 is a piston rod 26 having a piston 28 mounted thereon. The stem or rod 26 is formed with a screw threaded end 30 which may coact 75 with screw threads formed in the plug 12 whereby the pump construction may be closed or locked against movement.

The inner end of the stem or rod 26 is formed with a pointed end 32 which projects into the opening 16 in the web 14 for closing it when the pump is in inoperative position. Operation of the pump will force air through the passageway 24 against the ball valve 22 into the interior of the dispensing device.

The cylinder 10 is, of course, open to atmosphere by means of openings 34 formed in the plug 32. The base A has mounted thereon, an outside chamber 36. The lower end 90 of the chamber 36 rests upon a gasket or seal 38. The chamber or casing 36 may be provided with any means of connection between itself and the base A.

I have provided an outturned flange 40 95 which extends a short distance around the casing 36 and which coacts with a similar flange 42 formed upon the base A whereby the casing 36 after it is set upon the base A 100 may be turned a quarter turn and the flanges

40 and 42 coacting with each other, serve to retain the casing 36 in proper air tight position upon the base A.

5 The casing 36 in its head has a passageway 44 in communication with a valve controlled outlet B. The outlet B is screw threaded into the head of the casing 36 as at 46. A manually controlled valve element 48 is adapted to be seated against the valve seat 50.

10 The outlet B is formed with a downwardly extending spout 52. The passageway 44 is in communication with the valve B. Within the outside casing 36 I mount an inner container or casing 54 made of paper 15 or any other suitable material.

15 The container 54 is provided with an upturned inwardly extending flange 56. A bottom 58 is mounted within the container 54 and has a downwardly extending flange 60 20 adapted to rest against the inner wall of the container 54 and to coact with the upturned flange 56 thereof as clearly shown in Figure 5 of the drawings.

It will be noted that the bottom 58 is positioned a short distance above the lower end 25 of the container 54 so that a chamber or air receiving pocket 62 is formed above the base A and below the bottom 58. The passageway 54 in the base A is in communication 30 with the receiving pocket 62.

Within the container 54 may be placed substances of semi-liquid nature such as shaving cream, cleansing cream, tooth paste and the like.

35 The contents from within the container 54 is forced upwardly by means of the air pressure applied against the bottom 58. This in turn fills the passageway 44 and the valve element B with the substance or contents.

40 Inward movement of the valve control 48 manually, will allow a certain amount of the contents to pass around and through the valve seat 50 into the spout 52 where it will be dispensed. Pressure of the contents within 45 in the chamber 54 against the valve or control element 48 causes it to assume a closed position.

It will thus be noted that the element 48 is opened manually and closed automatically 50 by the pressure of the contents within the container 54. Movement of the valve element 48 is of course limited by the head or knob formed thereon which engages the spout or outlet B.

55 *Practical operation*

In the practical use of my device, it is only necessary to take a container as represented in Figure 5 of the drawings and place 60 it within the casing 36. The pump mechanism is released and thereafter reciprocated until air pressure is acquired within the receiving pocket 62.

65 The check valve 22 permits the air pressure accumulated within the pocket 62 to remain

therein while further pumping action takes place. After a sufficient amount of pressure has been built up in the pocket 62, then the pump may be locked against further operation.

The action just referred to places the contents within the container under pressure and whenever the valve element 48 is moved to open position, the contents will be discharged.

70 My device is especially applicable for use in barber shops and the like where shaving cream may be purchased in considerable volume, placed in my dispensing apparatus and dispensed in such amounts as required for shaving purposes.

75 Some changes may be made in the construction and arrangements of the parts of my device without departing from the real spirit and purpose of my invention and it is my intention to cover by my claims, any modified forms of structure or use of mechanical equivalents, which may be reasonably included within their scope.

80 I claim as my invention:—

1. In a device of the character disclosed, a 85 casing, a base separably connected with said casing, a pump in said base comprising a cylinder portion, a dividing wall in said cylinder portion having an opening therein, a piston, a stem for said piston, a handle thereon, a plug in one end of said cylinder, said stem and said plug having coacting threads, said stem having a pointed end adapted to coact with the opening in said partition, a plug in the other end of said cylinder, a check valve 95 in said last mentioned plug and a passageway leading from said check valve to said casing.

100 2. In a device of the character disclosed, a casing adapted to receive a carton having a movable bottom for discharging the contents of the carton, said casing having a passageway to receive such contents and a valve through which the contents may be discharged to atmosphere, a base separably connected with said casing, a pump in said base comprising a cylinder portion, a dividing wall in said cylinder portion having an opening therein, a piston, a stem for said piston, a handle thereon, a plug in one end of said cylinder, said stem and said plug having coacting threads, said stem having a pointed end adapted to coact with the opening in said partition, a plug in the other end of said cylinder, a check valve in said last mentioned plug and a passageway leading from said check valve to said casing.

110 3. In a device of the character disclosed, a casing, a base, a pump in said base comprising a cylinder portion, a dividing wall in said cylinder portion having an opening therein, a piston, a stem for said piston, a handle thereon, said stem having a pointed end adapted to coact with the opening in said partition, a plug on the other side of said 115 120 125 130

partition, a check valve in said plug and a passageway leading from said check valve to said casing.

4. In a device of the class disclosed, a casing, a base, a pump in said base comprising a cylinder, a piston therein, a stem for said piston, a handle thereon, a plug in one end of said cylinder, said plug having a head, a gasket under said head, a check valve in said plug discharging laterally therefrom and a passageway leading from said check valve through said passage to said casing.

5. A dispenser comprising an air tight casing having a closed end, a tube having an open end adapted to engage the closed end of said casing and having in its other end a movable wall or bottom, a passageway leading from said closed end and terminating in a valve controlled outlet, means for subjecting said bottom within said casing to pressure whereby when said valve is actuated to open position said bottom will move and a portion of the contents of said tube will be discharged from said valve, the pressure within said casing causing the tube to engage the closed end of the casing and constraining the valve to closed position.

Des Moines, Iowa, October 24, 1927.
